UNITED STATES PATENT OFFICE

158,220

HOUSING FOR COMBINATION SPACE
HEATER AND LOUDSPEAKER

David Sandler, Cleveland Heights, Ohio

Application May 10, 1949, Serial No. 2,556

Term of patent 3½ years

(Cl. D81—10)

To all whom it may concern:

Be it known that I, David Sandler, a citizen of the United States, residing in the city of Cleveland Heights, county of Cuyahoga, and State of Ohio, have invented a new, original, and ornamental Design for a Housing for Combination Space Heater and Loud Speaker, of which the following is a specification, reference being had to the accompanying drawings, forming a part thereof:

Figure 1 is a front elevation of a housing for combination space heater and loud speaker, showing my new design;

Figure 2 is a rear elevation of the same;

Figure 3 is a top plan view;

Figure 4 is a left end view of Figure 1; and

Figure 5 is a right end view of Figure 1.

The stippled portions in the several views indicate contrasting colored areas.

I claim:

The ornamental design for a housing for combination space heater and loud speaker, substantially as shown and described.

DAVID SANDLER.
